George Hare,
INVENTOR

BY *Victor J. Evans*
ATTORNEY

UNITED STATES PATENT OFFICE

GEORGE HARE, OF ST. PETERSBURG, FLORIDA

ATTACHMENT FOR SAWS

Application filed July 8, 1929. Serial No. 376,803.

The present invention relates to butcher saws, and saws of like construction, and contemplates the provision of a novel construction of means whereby a quick and positive tension of the blade can be effected.

Amongst other features, the invention embodies a rotatable disk having a connection with one end of the saw blade, together with a novel construction of means for adjusting the disk to quickly and positively tension the blade as the occasion may require.

Other objects and advantages will appear when the following detailed description is read in connection with the accompanying drawings, the invention residing in the construction, combination and arrangement of parts as claimed.

In the drawings forming part of this application like numerals of reference indicate similar parts in the several views, and therein:

Figure 1 is a side elevation of a saw illustrating one embodiment of the invention.

Figure 2 is a fragmentary end elevation.

Figure 3 is a sectional view on line 3—3 of Figure 1.

Figure 4 is a sectional view on line 4—4 of Figure 1.

Figure 5 is a fragmentary view of a modified construction.

Figure 6 is a sectional view on line 6—6 of Figure 5.

Figure 7 is a fragmentary view of a still further modified form of the invention.

Figure 8 is a sectional view on line 8—8 of Figure 7.

Referring to the drawings in detail, and more particularly Figures 1 to 4 inclusive, 10 indicates the blade of the saw which is mounted in the frame 11 of ordinary well known construction. The handle is indicated at 12. One end of the frame 11 is bifurcated as at 13 to receive the adjacent end of the blade 10, and is also formed with opposed slots 14 in which is arranged a pin 15 carried by the blade 10 as illustrated.

The means for effecting a quick and positive tension on the blade 10 essentially embodies a rotatably mounted disk 16 which op-

erates in the bifurcated portion 17 of the other end of the frame 11 as clearly illustrated in Figure 4. The disk is grooved as at 18 to receive the blade 10, and is also formed with notches 19 to receive the cross pin 20 carried by the adjacent end of the blade. The disk 16 is formed with a square central opening to receive the squared portion 21 of a supporting pin, which latter is also formed with an annular portion 22 fitted in a similarly formed opening provided in the frame 11. The pin is also provided with a reduced threaded extremity 23 which projects through an opening in the frame 11, and has associated therewith a nut 24 for holding the parts operatively associated. The other end of the pin supports a head 25 having a transverse bore 26 therethrough in which any suitable tool can be quickly inserted to rotate the disk as the occasion may require. Manifestly by turning the disk in the manner stated, the blade 10 can be quickly and positively tensioned with a minimum of effort. The disk is also provided with a series of teeth 27 with which the pawls 28 cooperate to prevent retrograde movement of the disk as will be readily understood.

In Figures 5 and 6 I have illustrated a modified form of the invention, although the principle of operation is exactly the same as hereinabove described in connection with the preferred form. In these views, the blade is indicated at 29 and is associated with the rotatable disk 30 in the same manner above described. In this form of the invention however, the disk 30 is mounted on an ordinary pivot of any well known construction, in contradistinction to the pin hereinabove described, while the disk is formed with a socket 31 to accommodate a suitable tool for turning the disk for the purpose above stated. The disk is also formed with teeth 32 which are engaged by pawls 33 to prevent retrograde movement of the disk.

In Figures 7 and 8 I have illustrated another modified form of the invention, wherein the same principle of operation is also carried into effect. However, in this form of the invention I contemplate the use of a hand

actuated lever 34 for operating the disk, in contradistinction to the means hereinabove described for this purpose. In these views, the disk is indicated at 35 and is connected with the saw blade 36 in the manner above set forth, the disk being formed with the usual teeth 37 to cooperate with the pawls 38 to prevent retrograde movement of the disk. The lever 34 is arranged in close relation to the handle 39 of the saw so that it can be gripped and conveniently operated as the occasion may require. Carried by the lever 34 is a pawl 40 which engages the teeth 37 to rotate the disk in one direction incident to the operation of the lever. Mounted upon the pivot for the disk 35 is a resilient washer 41 which is employed to exert a tension on the operating lever 34. It is manifest, that the invention in any of the forms herein illustrated and described, is simple in construction, and both efficient and positive in operation for the purpose intended.

While it is believed that from the foregoing description the nature and advantages of the invention will be readily apparent, I desire to have it understood that I do not limit myself to what is herein illustrated and described, and that such changes may be resorted to when desired as fall within the scope of what is claimed.

What I claim is:—

1. A saw comprising a frame, a blade detachably engaged with one end thereof, a disk mounted for rotation and formed with a peripheral groove to receive the other end of the blade, means for detachably connecting the last mentioned end of the blade with said disk, means for partially rotating the disk to obtain a quick and positive tension on the blade, and means for preventing retrograde movement of the disk, at different stages of the partial rotation thereof.

2. A saw comprising a frame, a blade detachably engaged with one end thereof, a disk supported upon the frame for rotation and having detachable association with the other end of the blade, a socket formed on said disk, whereby the latter can be partially rotated to effect a quick and positive tension on the blade, and means for preventing retrograde movement of the disk, at different stages of the partial rotation thereof.

In testimony whereof I affix my signature.
GEORGE HARE.
